UNITED STATES PATENT OFFICE.

CASIMIR D. BRODERICK, OF CHAZY, NEW YORK.

BULL-RING.

1,290,062.

Specification of Letters Patent.

Patented Jan. 7, 1919.

Application filed August 23, 1918. Serial No. 251,145.

To all whom it may concern:

Be it known that I, CASIMIR D. BRODERICK, a citizen of the United States, and a resident of Chazy, in the county of Clinton and State 5 of New York, have invented a new and Improved Bull-Ring, of which the following is a full description, reference being had to the accompanying drawing, forming a part thereof.

10 This invention relates to animal nose rings, such as anti-sucking or bull rings, and has for its object the production of a durable device capable of easy application and one which will not interfere with the animal 15 while eating.

This invention is distinguishable from other devices of its class in that it is divided into two parts or loops in its construction, one of such loops constituting a nose clamp 20 portion and the other loop which may correspond to the ordinary nose ring. This form of construction produces a much longer device than the usual nose ring and also acts as an anti-sucking device and prevents the 25 animal from getting any obstacle into its mouth, as the device practically extends almost across the animal's mouth acting somewhat in form of a muzzle.

Referring to the drawing
30 Figure 1 represents a plan view of my device, and

Fig. 2 represents a side view of the same. The device is preferably formed from a single piece of wire bent to approximately 35 the shape of a figure 8, thereby forming the arms 1 and 2 each embracing one side of the device. The two ends of the wire where they approach each other at the upper end or nose clamping portion of the device are 40 provided with enlarged or spherical nose clamps 3—3. Where the wire crosses itself to form the upper and lower loops each arm

of the device is preferably flattened as at 4—4 and each flat portion is perforated to receive means such as a bolt or fastening pin 45 5 to hold the arms together at this point. It will be seen that this construction divides the device into two portions, an upper or nose clamping portion and a lower loop which would practically extend across the 50 animal's mouth and form a protective or anti-sucking portion.

The usual method of applying the device is to remove the locking means 5 and press the arms 1 and 2 together where they form 55 the ring portion. This operation will separate the arms 1 and 2 which carry the nose clamping balls sufficiently to insert the same in the animal's nostrils. When pressure is removed the resiliency of the arms will cause 60 the nose clamp balls to firmly grip the septum of the animal's nose. The bolt or pin is then inserted and keyed in place, thereby locking the device.

It is obvious that the lower loop can be 65 used as a leading ring and when used as such the device cannot be pulled out of the animal's nose as any strain at the end on the lower loop portion would tend to tighten 70 the grip of the device on the nose.

It is obvious that any locking means may be used at the intersection of the arms 1 and 2 as long as the two arms are held practically rigid at this point.

What I claim is:

An animal nose ring formed of a single 75 piece of wire so bent as to form two loops, the upper loop being open at the top to form gripping jaws, and locking means at the intersection of the wire to form the loops and 80 for maintaining the relative position of the device.

CASIMIR D. BRODERICK.
